UNITED STATES PATENT OFFICE.

RICHARD DAVID METCALFE AND JAMES CROXON METCALFE, OF ROMILEY, ENGLAND.

EXHAUST-STEAM INJECTOR.

Application filed August 12, 1926, Serial No. 128,874, and in Germany August 24, 1925.

This invention relates to injectors which are worked by exhaust steam and in which a supply of live steam throttled down to a low or approximately atmospheric pressure 5 is used to work the injector when exhaust steam is not available.

In exhaust injectors of the type above referred to, the exhaust steam inlet has been closed (when exhaust steam is not available) by a valve operated upon by a piston 10 or valve to which live steam gains access from a hand control fitting as in the specification of our Re-issue Patent No. 16,398 granted July 27, 1926, United States Patent 15 No. 1,510,999.

Our present invention comprises an improved arrangement of valve which automatically closes the exhaust steam inlet if the injector be working with live steam 20 throttled down to low pressure and exhaust steam is not available, which prevents the flow of exhaust steam to the injector when the latter is not desired to work, and which is maintained in an open or mid-position 25 when it is desired to work the injector with exhaust steam.

Referring to the accompanying explanatory drawings:—

Fig. 1 is a sectional elevation and Figure 30 2 a sectional plan view of an exhaust injector having our improved valve arrangement applied thereto.

Figure 3 is a sectional plan view drawn to an enlarged scale of part of an exhaust 35 injector showing a modified construction of valve.

The same reference letters in the three views indicate the same parts.

The construction of exhaust injector illustrated 40 is similar to that in our prior application before referred to. *a* is the exhaust steam inlet, *b* the supplementary live steam inlet through which the live steam which assists in raising the delivery pressure of the injector enters the latter. *c* is the inlet for live steam throttled down to a low or to about atmospheric pressure for working the injector when exhaust steam is not available. *d* is the water inlet.

50 The exhaust valve *e* is carried by a stem *f* passing through guides at each end, the valve being adapted to seat on either of two seats *g* and *h*.

Within the cylinder *i* in the steam supply fitting at the entrance to the injector is a 55 piston *j*, the latter being adapted to bear upon the end of the stem *f* in order to prevent the exhaust valve *e* closing on the seat *h* under the pressure of the exhaust steam entering at *a* and passing into the injector. 60 When the piston is at the end of its operative stroke it abuts against the nut *k* which prevents the passage or leakage of steam along the piston. Steam is supplied to the cylinder *i* from a control fitting, not shown, 65 by way of the connection *m*, see Figure 2.

The action of the valve *e* is as follows:— Assuming that the injector is to be worked with exhaust steam from the passage *a* the operator admits live steam to the cylinder 70 *i* so that the piston *j* is moved against a seating on the nut *k* to the position shown. The valve *e* is forced off the seat *g* into the position shown by the exhaust steam so that such steam can pass into the injector. 75 If exhaust steam is present at *a* and the injector is not required to work, the steam is exhausted from the cylinder *i* by the control fitting, not shown, and the valve *e* is forced by the exhaust steam on to the seat *h* so preventing the steam passing through the injector and out at the overflow passages. 80

If the injector is to be worked by live steam throttled down to a low or about atmospheric pressure because exhaust steam 85 is not available, the valve *e* will be forced on to its seat *g* by the steam pressure within the injector, so preventing any escape of steam from the injector through the passage *a*.

In the arrangement shown in Figure 3, a fixed guide stem *c* is supported from the valve seat *g* and the valve *e* has a sleeve-like extension *f* against which the piston *j* abuts for the purpose before described. 95

Whilst the part *j* has been shown as a piston a valve which closes against the seat on the nut *k* when steam is admitted to *i* may be substituted therefor.

We claim:

1. In an injector a steam passage, a pair of spaced valve seats each encompassing said passage, a valve located in said passage between said seats and adapted to engage one or the other thereof to close the passage, 105 said valve being free at all times to be shift-

ed by steam flow through said passage in one direction to engage one of said seats and being free at some times only to be shifted by steam flow through said passage in the 5 opposite direction to engage the other of said seats.

2. In an ejector having a passage connecting exhaust and live steam inlets, a pair of spaced valve seats each encompassing said passage intermediate said inlets, a valve located between and adapted to engage one or the other of said seats, said valve being constructed and arranged to be automatically shifted toward one of said seats by exhaust 10 steam pressure and toward the other of said seats by live steam pressure, and means to hold said valve in an intermediate position between said seats against exhaust steam pressure under predetermined conditions.

20 3. In an injector having a passage connecting exhaust and live steam inlets, a pair of valve seats each encompassing said passage intermediate said inlets, a valve mounted between said seats and freely movable to engage one or the other of said seats under the influence of exhaust or live steam pressure respectively, and manually controlled 25 fluid pressure actuated means engaging said valve to permit its free travel only between one of said seats and a point intermediate said seats.

4. In an injector having a passage connecting exhaust and live steam inlets, a pair of valve seats each encompassing said passage intermediate said inlets, a valve slidably mounted between said seats and freely movable to engage one or the other of said seats under the influence of exhaust or live steam pressure, respectively and a fluid pressure 35 actuated piston operative under predetermined conditions to engage said valve to permit its free travel only between one of

said seats and a point intermediate said seats.

5. In an injector having a passage connecting exhaust and live steam inlets, a pair of aligned valve seats each encompassing said passage intermediate said inlets, a cylinder located longitudinally of the central axis through said seats, bearing members located in alignment with said cylinder, a valve stem slidably mounted in said bearing members and extending into said cylinder, a valve disc mounted on said stem intermediate said seats and having oppositely disposed faces adapted to engage one or the other of said seats to close said passage, and a freely movable fluid pressure actuated piston located in said cylinder and adapted to abut against said stem to limit its travel.

6. In an injector having a passage connecting exhaust and live steam inlets, a pair of aligned valve seats each encompassing said passage intermediate said inlets, a cylinder located longitudinally of the central axis through said seats, bearing members located in alignment with said cylinder, a valve stem slidably mounted in said bearing members and extending into said cylinder, a valve disc mounted on said stem intermediate said seats having oppositely disposed faces adapted to engage one or the other of said seats, a freely movable piston located in said cylinder, means for admitting fluid under pressure to said cylinder to force said piston to one end of the cylinder and thereby limit the travel of said valve stem, and means forming a fluid-tight joint between said piston and the end of said cylinder to prevent the leakage of fluid from the latter.
